CLAIM

The ornamental design for a cross shaped Christmas decoration, as shown and described.

DESCRIPTION

FIG. 1 is a perspective view of a cross shaped Christmas decoration showing my new design;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a bottom plan view thereof;

FIG. 7 is a top plan view thereof; and,

FIG. 8 is a perspective view thereof wherein a plurality of base legs shown in broken lines are attached to the cross shaped frame for the purpose of supporting the cross shaped Christmas decoration in an upright orientation.

The broken lines showing the supporting legs in FIG. 8 are included for the purpose of showing environmental structure and forms no part of the claimed design.
